MAGAZINE STAND OR SIMILAR ARTICLE

Ernst D. Payer, Moreland Hills, Ohio

Application July 25, 1950, Serial No. 11,399

Term of patent 7 years

(Cl. D33—2)

To all whom it may concern:

Be it known that I, Ernst D. Payer, a citizen of the United States and a resident of Moreland Hills, in the county of Cuyahoga and State of Ohio, have invented a new, original, and ornamental Design for a Magazine Stand or Similar Article, of which the following is a specification, reference being had to the accompanying drawing, forming a part hereof.

In said drawing, Fig. 1 is a front perspective view of a magazine stand or similar article, showing my new design; Fig. 2 is a top plan view thereof; and Fig. 3 is an end elevational view.

I claim:

The ornamental design for a magazine stand or similar article, as shown.

ERNST D. PAYER.
